UNITED STATES PATENT OFFICE.

CHARLES FRANCIS JENKINS, OF WASHINGTON, DISTRICT OF COLUMBIA.

RADIO VISION MECHANISM.

Original No. 1,530,463, dated March 17, 1925, Serial No. 708,531, filed April 23, 1924. Application for reissue filed March 15, 1927. Serial No. 175,690.

This invention relates to that class of instruments employed in radio vision, i. e., in the reception of radio signals representing active scenes, broadcasted from some distant sending station; and has for its main object the association of such parts as permit high speed and the required number of lines per inch for quality in the reproduction.

In the drawing Figure 1 is an elevation of 10 the instrument, and Figure 2 a sectional view; in both of which 1 is a supporting arm; 2 a prismatic plate (the subject of Patent No. 1,385,825); 3 a perforated disc having lens 4, 4', 4'', etc., mounted thereon. 15 The lens disc 3 is mounted on the shaft 5, on the opposite end of which a gear 6 is fastened. Gear 6 engages with a larger gear 7 on the shaft 8 together with the gear 9, which latter meshes with the gear 10 on the 20 sleeve shaft 11 upon which latter the prismatic disc is carried, the gear sizes being such as to multiply the rotative speed of lens disc 3 over the prism disc 2. On the upper end of the arm 1 a lantern 12 is supported, enclosing lamp 13, which is attached to a suitable radio set 14. 15 is a crank by 25 which the mechanism may be rotated. 16 is a screen upon which the picture appears.

The filament of the lamp 13 is imaged 30 through the lens 4 onto the screen 16 as a point of light 17. The movement of the lens, by reason of the rotation of the disc, causes this point of light to move from left to right (Fig. 1) in an arc across the screen 35 16, and as the light beam passes through the prism 2 it is deflected from the centre line of the optical system and travels across the screen near the top. The following lens does exactly the same thing, that is, it makes the 40 spot of light move across the screen from left to right, as does every other succeeding lens. These lines of light would all fall in the same place except for the fact that the prismatic ring is rotating, and, therefore, 45 because the prism, radially considered, behind each lens is angularly less, the lines of light on the screen lie adjacent and parallel in a horizontal direction until with one turn of the prism (2) the screen has been covered with parallel lines from top to bottom, the lines being made by the lenses, and 50 their disposition on the screen determined by the prismatic ring or plate or disc.

As each lens makes its own individual line and does not repeat until the lens disc has 55 made one complete circle, the first lens considered will make the first line, the 13th line, the 25th line, etc., while the next lens will make the 2nd line, the 14th line, the 26th line, etc. The number of lines over the 60 whole screen is, therefore, determined by the number of lenses on the disc multiplied by the ratio of the gears which connect the lens disc and the prism disc. For example, if the lens disc has 12 lenses thereon, and the 65 gear ratio is six to one, there will be 72 parallel lines from the top to the bottom of the screen. Of course, the number of lenses and the gear ratio may be anything desired.

As the incoming radio signal increases 70 and decreases the intensity of the light source (13), obviously the brilliancy of the spot on the screen is determined by the strength of the incoming radio signals at the moment considered. If, therefore, the rotation of the mechanism is in synchronism 75 with the rotation of the mechanism at the sending station; and the incoming signals represent in their strength the light value of the picture at the sending station, it will 80 readily be seen, that the picture on the screen 16 will be a duplicate of the active scene in front of the lens at the sending station, assuming the speed of the two machines to be such that by reason of persistence of vision the eye is deceived into the 85 belief that it is looking at the whole of the picture all of the time.

It will be apparent to one skilled in the art, that the operation of my invention is 90 reversible, that is, the apparatus shown may be used as a scanner for analyzing a picture situated at 16 and translating the successive light variations into like electrical current variations by substituting for lamp 13 a 95 light sensitive cell.

Of course, I do not wish to limit myself to circularly moving lenses or to a circular prism as it is quite obvious that other combinations of lenses and a constantly angularly-changing prism may be employed 100 without departing from the spirit of my invention.

It will be understood that crank 15 is merely symbolic of any suitable means for 105 rotating the mechanism, and that suitable

means is provided for maintaining such driving means in synchronism with the mechanism at the sending station.

What I claim is:

5. 1. The combination of a prismatic disc and a lens-carrying disc, and means for rotating one in front of the other.
2. The combination of a prismatic disc and a lens-carrying disc, and connecting means for rotating one disc in front of the other, and at differing speeds.
10 3. The combination of a series of lenses, means for passing a pencil of light through said lenses in succession, a prism through 15 which the light pencil also passes, and means for changing the angle between the faces of the prism at the point where the light passes therethrough.
4. The combination of a prismatic disc, 20 a sleeve-mounting for same, a lens-carrying disc, a shaft-mounting therefor, said shaft supported inside said sleeve, and a gear connection between to give the sleeve and shaft different rates of rotation.
25 5. The combination of a stationary picture surface, a stationary light translating device, means comprising a lens for forming images of said stationary elements each upon the other, means for moving said image-forming device to cause the images to successively traverse the stationary elements, a prism through which the light passes and means for changing the angle between the faces of the prism for causing successive 30 traversals to cross said elements by different paths.
6. In combination, a stationary picture surface, a stationary light translating device, a movable lens for forming a beam of light and causing it to traverse said surface successively, a prism through which the beam of light passes, and means for changing the angle between the faces of the prism for causing successive traversals to cross said 35 surface by different paths.
40 7. In combination, a stationary picture sur-

face, a stationary light source, a plurality of movable lenses for forming beams of light from said source and causing them to traverse said surface successively, a prism 50 through which the beams of light pass common to said lenses, and means for changing the angle between the faces of the prism for causing successive beams to cross said surface by different paths.

55 8. The combination of a stationary picture surface, a stationary source of light, a rotatable light distributing member having mounted thereon a plurality of lenses for causing a succession of beams of light 60 to traverse said surface, a prism through which the beams of light pass common to said lenses, and means for changing the angle between the faces of the prism for causing successive beams to cross said 65 surface by different paths.

9. The combination of a stationary picture surface, a stationary source of light, a rotatable light distributing member located between said surface and light, said member 70 being provided with a plurality of apertures to cause a succession of beams of light to traverse said surface, a prism through which the beams of light pass common to said apertures, and means for changing the 75 angle between the faces of the prism to cause successive beams to traverse the surface by different paths.

10. The combination of a stationary picture surface, a stationary light translating device, a plurality of lenses for forming images of one of said parts on the other each upon the other, means for moving said lenses to cause a succession of images to traverse the image plane, a prism through 80 which the light passes common to said lenses, and means for changing the angle between the faces of the prism for causing successive 85 images to traverse said image plane by different paths.

In testimony whereof I affix my signature.
CHARLES FRANCIS JENKINS.
